UNITED STATES PATENT OFFICE

FRANCIS S. AUSTIN, OF PITTSBURGH, PENNSYLVANIA, ASSIGNOR TO CARBO-OXYGEN COMPANY, OF PITTSBURGH, PENNSYLVANIA, A CORPORATION OF DELAWARE

BLOWPIPE

Application filed April 2, 1930. Serial No. 441,054.

This invention relates to blowpipes such as are employed for the purpose of cutting metal, and has for its general purpose and object to provide a blowpipe of this character which is particularly adapted for the removal of protuberances, such as rivet heads, from metal as well as for the removal of seams from billets or other metal masses prior to rolling the same, this seam-removing operation being referred to in the art as "scarfing" or "de-seaming." In the operation of de-seaming or scarfing, it is highly desirable to prevent the cutting oxygen from penetrating any material depth into the mass of the metal and, in the operation of removing protuberances, such as rivet heads, it is also highly desirable to accomplish such removal without any material penetration into the body of the metal from which the protuberance projects.

I accomplish the foregoing general objects in and through the construction and arrangement of parts shown in the accompanying drawings, wherein Fig. 1 represents a side elevation of a cutting torch which may be employed as a means for embodying my invention; Fig. 2 a sectional central view through a blowpipe head and tip embodying my invention, the sectional view including the ends of the pipes connected to the head; Figs. 3, 4 and 5 are sectional views corresponding respectively to the lines 3—3, 4—4 and 5—5 of Fig. 2; Fig. 6 a plan view of the valve block and part of the tubular handle of the blowpipe; Fig. 7 a sectional detail corresponding to the line 7—7 of Fig. 6; and Fig. 8 a detail in section through the rear end of the valve block and showing a modification of the valve controlling the supply of cutting oxygen.

The blowpipe shown herein is of the same general type as that illustrated and described in the joint application of myself and Lorn Campbell, Jr., filed May 31, 1928, Serial No. 281,950, which has resulted in Patent No. 1,830,459, issued November 3, 1931.

Describing the various parts by reference characters, 1 designates a valve block which is provided with a connection 2 for oxygen and a connection 3, controlled by a valve the handle of which is shown at 4, for combus-

tible gas. The valve block, as is common in the art, is provided with a valve operated by a lever 5 for controlling the supply of cutting oxygen through a pipe 6 to the head. It is also provided with a passage controlled by 55 a valve 7, for supplying preheating oxygen through the pipe 8 to such head; while 9 denotes a pipe leading from the block for conducting the combustible gas to the head. From the valve block, a tubular handle 10 extends forwardly, surrounding the parts of the pipes 6, 9 and 8 adjacent to the block. The forward or delivery ends of the pipes 6, 9 and 8 are secured to the rear end of the head 11 of the blowpipe.

Above the pipe 8, the head is provided with an upwardly and forwardly inclined seat 12, which seat is pierced by a bore 13 extending downwardly and forwardly toward the upper portion of a chamber (to be described hereinafter) formed within the upper portion of the bore 14, which extends upwardly from the bottom of a front extension 15 of the head. The bore 13 is provided with an annular enlargement 13^a at the rear thereof 70 forming an annular distributing chamber with the mixing plug; the remainder of the bore is internally threaded, as shown at 13^b. Threaded into the bore 13 is a mixing plug 16 having a head 17 provided with a slot 17^a 80 for the reception of a screw driver and having, on the rear or underside of said head, a beveled surface 17^b adapted to engage the correspondingly beveled seat 12 at the outer end of the bore 13. This plug is provided with a 85 reduced body portion 16^a extending from the head thereof and forming the annular distributing chamber 18, referred to hereinbefore, with the part 13^a of the bore 13. The body of the plug is provided with two externally threaded portions, as shown at 21, thereby to provide an annular chamber 22 within the bore 13. The plug is provided with a central bore, the upper portion 23 of which is of smaller diameter than the lower portion 23^a. The upper end of the bore 23 communicates with the chamber 18 by means of ports 24, while the upper end of the bore 23^a communicates with the chamber 22 by means of ports 25. The lower end of the bore 100

23^a communicates with a chamber 26 formed in the bottom of the bore 13.

The pipe 8 delivers preheating oxygen into the chamber 18 through a bore 27 in the head 11 and the pipe 9 delivers combustible gas to the chamber 22 by means of a bore 28 in such head.

29 denotes a reduced internally threaded extension of the bore 14, projecting into the head, there being a tapered seat 29^a at the upper end of this threaded extension and a chamber 30 above said seat. An elongated upwardly inclined bore 31 in the head 11 establishes communication between the chamber 30 and the pipe 6 for cutting oxygen.

The upwardly extending bore 14, 29 and 29^a is provided for the reception of a tip, which will now be described. This tip comprises generally an inner member A and an outer member B. The inner member has a tapered or frusto-conical lower end A', a reduced tapered or frusto-conical intermediate portion A², and a cylindrical upper portion A³. Projecting from the portion A³ is an externally threaded head A⁴. At its extreme upper end, the inner tip member is provided with a beveled surface A⁵ cooperating with the seat 29^a. The cylindrical body A³ is provided with a plurality of longitudinal slots 32 which extend from the lower end thereof nearly to the upper end of such cylindrical portion. Three such slots are shown, but the number may be varied as desired without departing from my invention. The lower frusto-conical part A' is provided with a plurality of slots 33, six such slots being shown, though the number also may be varied as desired without departing from my invention.

The outer member B is shown as fitted to the inner member, as by swaging, and surrounds the major portion of the cylindrical part A³ and the remainder of the inner tip member below such cylindrical portion. This arrangement provides an annular chamber 34 in the head above the outer tip member and with which the upper ends of the slots 32 communicate.

35 denotes a pair of bores extending from opposite sides of the chamber 26 to opposite sides of the upper end of the chamber 34. These bores are of restricted cross-sectional area for the purpose of minimizing any propagation of flame from the chamber 34 into the said bores and into the passages and pipes therebeyond; and they deliver the mixture of preheating gases tangentially into and at each side of the said chamber 34, whereby the gases are whirled and mixed within said chamber.

60 The preheating mixture is delivered from the slotted passages 32 into the chamber C formed between the outer tip member and the part A² of the inner tip member, and thence into the slotted passages 33.

65 The chamber 30 is arranged axially above

the central bore 36 in the inner tip member, the central bore being intended to deliver cutting oxygen to the metal which has been preheated by the mixture delivered through the passages 33.

70 The valve block 1 is shown in detail in Figs. 6, 7 and 8 and preferably is a casting having the threaded connections 2 and 3 referred to hereinbefore and also valve-controlled passages for delivering the oxygen and the combustible gas to the pipes 6, 8 and 9.

75 The oxygen from the connection 3 is delivered into a chamber 40 from which a passage 41 leads to a chamber 42 having a valve seat 43 at its bottom arranged to be closed by a ball valve 44 which is pressed to its seat by a light spring 45, the lower end of the spring engaging the ball and the upper end of the spring being seated in a cap 46 which is threaded into the top of the chamber. From the chamber 42 a short passage 47 delivers the preheating oxygen to a chamber 48, the supply of oxygen to such chamber being controlled by a valve 49 threaded into the chamber and having a conical end 49^a cooperating with the valve seat at the chamber end of the passage 47. From the chamber 48, the preheating oxygen is delivered through a short port 50 to a bore which communicates with the pipe 8.

80 At the top of the chamber 40 is a valve seat 51 which is adapted to be closed by a valve 52 within the chamber 40 and having a stem 53 extending through a smaller chamber 54 and through the top of the valve block, the escape of the gas around the outer end of the stem being prevented by packing 55 and a locking plug 55^a. The upper end of the stem 53 is arranged to be engaged by 105 the lever 5 which has its rear end pivoted between lugs 56 projecting from the block.

85 From the chamber 54, a passage 57 conducts cutting oxygen to the pipe 6.

90 The connection 2 for the combustible gas delivers the said gas to a passage 58 whence it is delivered through a vertical passage 59 to a chamber 60, the flow of the gas to said chamber being controlled by a needle valve 61 cooperating with a valve seat 61^a at the chamber end of the passage 59, the needle valve being threaded into the outer end of the chamber 60. From the chamber 60, a passage 62 delivers the combustible gas to the pipe 9.

95 It should be noted that the cross-sectional area of the interior of the pipe 6, of the passage 31, and of the bore 36 are substantially the same, the cross-sectional area of the bore 36 being greatly enlarged as compared with the bores of blowpipe tips heretofore in common use for the cutting of metal with oxygen. This cross-sectional area is approximately twice the cross-sectional area of the delivery portions of cutting-oxygen bores in 100

5 tips having the same preheating capacity as mine and is greatly in excess of the cross sectional areas of the slots or passages 33 for the preheating mixture. Furthermore, the conduit formed by the bore 36, passage 31, and the pipe 6 extends without reduction in cross-sectional area to the chamber 54, it being noted that the passage 57 is also of substantially the same internal diameter as the 10 pipe 6.

10 It follows that, from this construction and arrangement of parts, when the metal shall have been preheated in the ordinary manner by the burning jets delivered from the passages 33 and the valve 52 shall have been opened, the pressure and velocity of the cutting oxygen at the delivery or operating end of the tip will have been greatly reduced, as compared with the pressure and velocity of 20 the cutting oxygen in blowpipes as ordinarily constructed, due to the large cross-sectional area of the conduit extending to and including such end. This enables me (in the case of projections such as rivet 25 heads) to remove the heads without penetrating the metal of the plate or body from which such head or protuberance may project. In the case of seams in billets and the like, it enables me to eliminate such seams, 30 but without penetrating or cutting into the body of the metal mass with the cutting oxygen, with the result that the billet or other body thus treated can be rolled without the development of cracks or seams therein.

35 In order to adjustably limit the opening of the valve 52, thereby to enable me to set the valve for any desired pressure and/or velocity of oxygen through the conduit leading to the operating end of the torch, I have 40 provided the valve with a stem 62, which is threaded into the central portion of the body of the valve 52 and which extends downwardly therefrom, the stem 62 being conveniently formed as a short screw having a slotted head 62^a whereby it may be threaded more or less into the valve 52. Mounted on 45 the stem 62 is a lock nut 63 which serves to retain the stem 62 in any position to which it may be adjusted.

50 When the cutting oxygen is not required, the valve 52 is normally seated, as is the usual practice, by a helical spring 64, the upper end of which bears against the bottom of a hollow plug 65 which is threaded in the bottom of 55 the chamber 40. It is evident that, by depressing the lever 5 in the usual manner, the valve 52 will be opened a distance depending upon the adjustment of the screw 62, the amount of such opening being limited by the 60 engagement of the head of the screw with the interior of the head of the plug 65; also that the extent of opening may be varied by adjustment of the screw 62.

65 In Fig. 8 there is shown a modification of my invention, wherein the valve 52^a is pro-

vided with a short lower stem 66 serving to center the spring 64, but which does not constitute a stop to limit the opening movement of the valve. However, the extent of opening of the valve 52^a in this case is controlled by varying the extent of throw which may be imparted to the valve by the lever 5. For this purpose, the part of the lever immediately above the stem 53 is provided with an internally threaded bore 67, in the lower part of which there is threaded a plug 68 having an upwardly convex bottom 68^a and having in the top a slot 68^b for the reception of a screw driver. By rotating the plug 68 in the appropriate direction, the distance which the lever 5 must be moved before unseating the valve 52^a may be varied as desired; and the plug may be locked in the position to which it is adjusted by means of a locking plug 69 threaded into the top of the bore 67 and also provided with a slot 69^a for the reception of a screw driver. As is well known, the throw of the lever 5 is limited by its engagement with the handle casing 10; and the variation of the position of the plug 68 in the lever 5 will effect a corresponding variation in the extent of opening of the valve 52^a when the front of the lever engages such handle casing.

95 In both forms of my invention, means are provided for adjustably limiting the extent of opening of the cutting-oxygen supply valve through the operation of the lever 5. Furthermore, while I have shown and described my invention as embodied in a particular construction of blowpipe head, valve block, and tip, it will be obvious that other forms and constructions of the aforementioned parts may be employed without departing from the spirit of my invention.

100 Having thus described my invention, what I claim is:

1. A blowpipe comprising in combination a tip having a bore for cutting oxygen and passages for delivering a mixture of preheating gases to the delivery end of said tip adjacent to the said bore, a head to which the said tip is secured, a passage for cutting oxygen in said head, a pipe connected with said head for supplying cutting oxygen to said passage, a valve for controlling the supply of cutting oxygen through said pipe, the conduit formed by said pipe, passage and bore being unobstructed and of substantially the same cross sectional area throughout its length and being of materially greater cross sectional area than the cross sectional areas of the said passages, and means for adjustably limiting the opening movement of the said valve, thereby to vary the pressure and velocity of the oxygen delivered into said conduit.

115 2. A blowpipe comprising in combination a tip having a bore for cutting oxygen and passages for delivering a mixture of pre-

- heating gases to the delivery end of said tip adjacent to the said bore, a head to which the said tip is secured, a conduit including said bore, a valve for controlling the supply of cutting oxygen through said conduit, the conduit being unobstructed and of substantially the same cross sectional area throughout its length from the delivery end of said bore to said valve and being of materially greater cross sectional area than the cross sectional areas of the said passages, and means for adjustably limiting the opening movement of the said valve, thereby to vary the pressure and velocity of the oxygen delivered into said conduit.
3. A blowpipe comprising in combination a tip having a bore for cutting oxygen and passages for delivering a mixture of preheating gases to the delivery end of said tip and adjacent to the said bore, a head to which the said tip is secured, a conduit including the said bore for cutting oxygen, and a valve controlling the supply of oxygen to said bore, the said conduit being of substantially the same cross sectional area throughout its length from the delivery end of said tip to said valve and being of materially greater cross sectional area than the cross sectional areas of said passages.
4. A blowpipe comprising in combination a tip having a bore for cutting oxygen and passages for delivering a mixture of preheating gases to the delivery end of said tip and adjacent to the said bore, a head to which the said tip is secured, a conduit including the said bore for supplying cutting oxygen thereto, the said conduit being of substantially the same cross sectional area throughout its length and being of materially greater cross sectional area than the cross sectional areas of the said passages, a valve for admitting cutting oxygen to said conduit, and means for variably limiting the extent of opening of the said valve.
5. A blowpipe comprising in combination a tip having a bore for cutting oxygen and means for delivering a mixture of preheating gases to the delivery end of said tip adjacent to the said bore, a head to which the said tip is secured, a conduit including the said bore for cutting oxygen, a valve block having a chamber therein with which the receiving end of said conduit communicates, the said chamber having a valve seat at the bottom thereof and a chamber extending from and below said seat, a valve in the second chamber and cooperating with said seat, means for supplying oxygen to the chamber below the said seat, a spring in the second chamber engaging the valve and tending to hold the same to its seat, the said valve having a stem extending through the first chamber and through the valve block, means on the valve block adapted to depress the stem thereby to unseat the valve, and an adjustable stop secured to and extending from the valve and adapted to engage the bottom of the second chamber thereby to variably limit the opening of the valve by the said means.
6. A blowpipe comprising in combination a tip having a bore for cutting oxygen and means for delivering a mixture of preheating gases to the delivery end of said tip adjacent to the said bore, a head in which said tip is mounted, a conduit including the said bore for cutting oxygen, a valve block having a chamber therein with which the receiving end of said conduit communicates, the said chamber having a valve seat at the bottom thereof, and a chamber extending from and below said seat, a valve in the second chamber and cooperating with said seat, means for supplying oxygen to the chamber beneath the said valve, the said valve having a stem extending through the first chamber and through the valve block, a lever pivotally mounted on the valve block and extending across the projecting end of the stem and adapted to depress the latter thereby to unseat the valve, a screw threaded into the valve and extending into the second chamber, means for securing the said screw in adjusted position, a cap closing the bottom of such second chamber, and a spring within the second chamber and bearing at one end against the cap and at its opposite end against the said valve and tending to seat the latter.
7. A blowpipe comprising in combination a tip having a bore for cutting oxygen and means for delivering a mixture of preheating gases to the delivery end of said tip adjacent to the said bore, a head in which said tip is mounted, a conduit, including the said bore, for cutting oxygen, a valve block having a chamber therein with which the receiving end of said conduit communicates, the said chamber having a valve seat at the bottom thereof, and a chamber extending from and below said seat, a valve in the second chamber and cooperating with said seat, means for supplying oxygen to the chamber beneath the said seat, a spring tending to hold the valve to its seat, the said valve having a stem extending through the first chamber and through the valve block, means on the valve block adapted to depress the stem thereby to unseat the valve, a screw adjustably connected to the valve and extending into the second chamber, and means for securing the said screw in adjusted position.
8. A blowpipe comprising in combination a tip having a bore for cutting oxygen and means for delivering a mixture of preheating gases to the delivery end of said tip adjacent to the said bore, a head to which the said tip is secured, a conduit including the said bore for cutting oxygen, the said conduit being of substantially the same cross sectional area throughout its length, a valve block having a chamber therein with which the receiving

end of said conduit communicates, the said chamber having a valve seat at the bottom thereof, and a chamber extending from and below said seat, a valve in the second chamber 5 and cooperating with said seat, means for supplying oxygen to the chamber beneath the said valve, a spring in the second chamber engaging the bottom of the valve and tending to hold the same to its seat, the said valve having 10 a stem extending through the first chamber and through the valve block, a lever pivotally mounted on the valve block and extending across the projecting end of the stem and adapted to depress the latter thereby to 15 unseat the valve, and means limiting the movement of the lever in a direction to open the valve.

In testimony whereof, I hereunto affix my signature.

20 FRANCIS S. AUSTIN.
